COIL FORMING DRUM

Frank L. Wettengel, Pittsburgh, Pa.

Application October 9, 1940, Serial No. 360,479

37 Claims. (Cl. 242—78)

This invention relates to improved means for forming coils of strip metal, particularly strips of magnetic iron or steel in conjunction with cold reducing mills or any other processing equipment requiring the coiling of the strip.

This invention embodies the economic coiling of all kinds of strip, particularly steel strip, after the various processings through which it passes especially where the strip is coiled under tension beyond the elastic limit of the steel.

This coiling is done on various forms of cylindrical drums, viz; solid drums and collapsible-expanding drums. The collapsible expanding type of drums which necessarily are of the overhung or cantilever type are preferable because when the drum is collapsed the coil can be removed or stripped bodily, longitudinally with the axis of the drum.

Most of these coiler drums consist of a long shaft, the rear approximate half being provided with the necessary driving gears and the shaft is mounted in bearings of a drive frame necessary to rotate the drum. The front or overhung portion of the shaft carries the drum which usually consists of several segments hinged to each other, forming a cylindrical drum which is longitudinally, rotatably mounted on said overhung shaft. The segments are expanded and collapsed by various means such as wedges, rollers, toggles and cams formed on portions of the segments and on the shaft inside the drum segments while the collapsing is accomplished with springs.

It is advantageous when coiling thin material to keep the drum as small in diameter as possible so the thin limber inside convolutions will retain their cylindrical shape and not collapse filling and slipping out sideways from the hollow center of the coil thus preventing mounting the coil for future processing.

It is obvious especially in the small diameter drums that due to the space occupied by these many roller expanding parts that the cam shaped shaft inside the drum is smallest and weakest at the end of the segments near the drive where it should be the strongest.

Where rollers and cams are used to expand the segments it is obvious there is only a line contact between the various parts and this line contact is only effective about half of the length of the drum due to the necessity of holding the rollers, etc., in place with bearings, cages and other devices and no material has been found that will withstand this line contact crushing effect of the larger coils.

In this type of drum the segments are held in 55 drum than is possible with the present designs.

expanded position by the rollers passing the ridge of the cam and when collapsed it happens very suddenly and with thin material being coiled due to the friction against each other the inner convolutions do not have time to adjust themselves to the smaller drum diameter resulting in the outer convolutions crushing and causing wrinkles or corrugations in the inner convolutions which makes them commercially useless and it also makes it very difficult to remove the coils from the drum.

It is apparent that an overhung drum with a shaft progressively increasing in diameter from its overhung end and attaining the largest diameter at its supporting bearing is a distinct advantage in view of the heavy tension it must exert on the strip as well as sustain the weight of a coil weighing 25,000 pounds or more.

While the foregoing describes very briefly a 20 part of the coiling art and some coiling equipment with the difficulties encountered, it will be obvious to those skilled in the art that there are numerous deviations from the above.

With the object of eliminating as many of the 25 coiling difficulties as possible some of which are outlined above, I have devised a new design of coiling drum of the collapsible-expanding type with its necessary auxiliary equipment, and I have adapted to this type of drum as an additional 30 feature, the use of embedded electromagnet coils to magnetize the entire drum surface which will attract the strip end which becomes attached to the revolving drum and is carried around it for the first convolution.

Some of the other objects of this invention 35 are to—

Provide a new design of coiling drum of the overhung or cantilever type wherein the segments upon longitudinal movement are expanded and collapsed on and between inclined surfaces integral with the rotating shaft.

Provide a drum, without rollers or cams, in 40 which the crushing effect of the coil on the segments is distributed over large surfaces of the shaft instead of the short line contacts of the rollers and cams.

Provide a drum in which a larger diameter 45 rotating shaft replaces, roller expanding mechanisms with the shaft diameter progressively increasing from its overhung end toward its supporting bearing where the bending moment is the greatest.

Provide a drum whose shaft diameter is larger 50 therefore stronger for a minimum diameter of

thus being capable of producing, without bending, a coiling tension in steel strip beyond the elastic limit of the strip with a smaller diameter drum.

Provide hydraulic or screw and nut mechanism to produce longitudinal movement of the drum segments on the rotating overhung shaft which will positively collapse or expand the drum.

Provide rotating clutching means to operate the nut on the screw which will collapse, expand or hold the drum in any desired locked position, and at any desired speed, and by limit switch mechanism will positively and completely disconnect the rotating means from the nut when the drum becomes completely collapsed or completely expanded.

Provide current supply switch, telescoping conductors and collector rings for energizing electro-magnetic coils embedded in the drum segments which are arranged so the magnetic poles of the segments come in direct contact with and produce greater attraction for the strip, the end of which will be attracted and attached to the magnetized segments, thus adhering to the drum and be wound around its surface as it revolves thus forming the first convolution of the coil.

Provide coiling equipment that is simple of design; will have the desired very sturdy construction, be economical to manufacture, install, maintain and operate and also embodies other valuable advantages and novel features which will be apparent from the following detail description taken in conjunction with the accompanying drawings wherein like numerals represent corresponding parts in the various figures.

To the foregoing objects and to others which may hereinafter appear, the invention consists of the novel construction, combination and arrangement of parts as will be more specifically referred to and illustrated in the accompanying drawings wherein are shown embodiments of the invention, but it is to be understood that changes, variations and modifications may be resorted to which fall within the scope of the invention as claimed.

In the drawings:

Figure 1 is a longitudinal vertical section of a complete coiling unit with a magnetic coiling drum hydraulically collapsed and expanded and constructed in accordance with the features of the present invention.

Figure 2 is an enlarged longitudinal section on the line 2-2 of Figure 6 showing the magnetic collapsible-expanding coiling drum.

Figure 3 is an enlarged section through the extendible connector contact for the electro-magnetic coils.

Figure 4 is a longitudinal vertical section of a motor operated, magnetic clutch connected, collapsible-expanding mechanism with its schematic wiring control diagram.

Figure 5 is a longitudinal vertical section of another form of a motor operated, friction clutch connected, collapsible-expanding mechanism, with its schematic wiring and piping control diagram.

Figure 5A is a fragmentary sectional view of the solenoid operated valve in another position.

Figure 6 is a transverse vertical cross section of the magnetic, collapsible-expanding coiling drum taken on the line 6-6, Figure 2.

Figure 7 is a transverse vertical cross section of the magnetic, collapsible-expanding coiling drum taken on the line 7-7, Figure 2.

Figure 8 is a transverse vertical cross section

of the collapsible-expanding mechanism taken on the line 8-8, Figure 4 and Figure 5.

Figure 9 is a transverse vertical cross section of the collapsible-expanding mechanism taken on the line 9-9, Figure 4 and Figure 5.

Figure 10 is a fragmentary view of the telescopic joint between the collapsible drum segments, looking radially toward the center of the drum, the arch plates being removed.

Figure 10A is a view similar to Figure 10 but showing a dovetail joint between the segments.

In the embodiments of this invention herein illustrated in the various figures, there is first provided in Figure 1, a magnetic collapsible-expanding cylindrical coiling drum consisting of a hollow central driving shaft 1, supported in the manner of a cantilever by a combined radial and thrust bearing 2, on the rear end of the shaft and a parallel bearing 3, near the longitudinal center 15 of the shaft with the overhung end of the shaft forming the core of the drum. In these specifications the expression "front" or "front end" means the end at the right hand of illustrating Figures 1-2-4-5 and conversely "rear" or "rear end" means the left hand end.

The bearings are mounted or carried by a drive frame or housing 4, made in suitable sections for assembling and dismantling. A drive gear 5 is keyed to the shaft 1, and meshes with a pinion 6, carried by shaft 1, which is rotatable in bearings 8. The bearings 8 are held by retainers 9, and the shaft 7 is connected to a motor 10 by coupling 11. A brake 12, spring set and magnetic released in series with the motor, arrests and prevents rotation of the shaft 7 when motor 10 is not in operation. Outer races of bearing 2, also of bearing 3, are held in the drive frame 4 by retainers 13 and 14, respectively. The single reduction drive illustrated and described above is 30 only a typical arrangement. Double reductions and other arrangements of motor and gears are 40 equally adaptable for rotating the shaft and drum.

The coiling drum proper is shown in larger 45 scale in Figures 2, 3, 6, 7 and 10. The drive shaft-drum core 1 is the foundation around which the collapsible-expanding cylindrical drum to be hereinafter described and consisting of segments 50 together with the necessary collapsing-expanding discs, rings, etc., are built, all of which will first be described without the magnetic feature. The drive shaft-drum core 1 is a hollow shaft provided outwardly of the anti-friction bearing 3 with a plurality of spaced apart frusto-conical 55 surfaces of which 15 is the innermost and largest in diameter, 16 is the intermediate surface and smaller in diameter than surface 15 and 17 is the outermost and is smaller in diameter than surface 16. The shaft 1 is formed with a stud 18 at its outer end which serves to support and keep the various drum members concentric.

The outer periphery of the cylindrical drum is 60 formed of a plurality of segments and in the present instance with three segments 19, whose outside diameters correspond to the expanded drum diameter and whose inside diameters when collapsed are somewhat larger than the shaft drum core 1. On the internal surface of these segments are provided internal frusto-conical 65 surfaces 15^a, 16^a and 17^a co-related when the segments are expanded with surfaces 15-16 and 17, respectively, on the shaft drum core. The rear ends of these segments are provided with an 70 external frusto-conical surface 20 and the in-

ternal diameter 24 is a continuation of frusto-conical surface 15^a but slightly larger.

At the rear end of the segments is provided a retaining collar 22 fixed to the shaft drum core 1 as by a key or the like and recessed as at 22^a to provide for the longitudinal movement of the segments 19. The collar 22 is also formed with a recess 22^b to house a collapsing ring 23, a portion of whose internal diameter overlies the recess 22^a and corresponds to the external diameter of the expanded segments forming the drum. Another portion of the ring 23 is formed with an internal frusto-conical surface 20^b corresponding with the frusto-conical surface 20 of the segments. Sleeves 24 and 25 are carried by the shaft 1 on opposite sides of the bearing 3 and position and retain the inner race of the bearing 3 in place.

The front ends of the segments 19 are provided with projecting tongues 26 whose shape are frusto-conical each of whose width is only about half of the segment width. On the outer end of the shaft drum core 1 is attached a collapsing disc 27 (partly broken away in Figure 6 to show the tongue 26 more clearly) formed with segmental slots 28 slightly wider than the projecting tongues 26 and the large diameter surface of the slot corresponds with the frusto-conical surface of the projecting tongues 26. All of these external and internal frusto-conical surfaces have the same angle with relation to the axis of the drum core and short longitudinal movement produces practically parallel movement of the segments 19.

The front ends of the segments 19 are provided with a right angular extension 29 which also forms an internal flange for collapsing the segments 19. The outside diameter of this extension 29 is concentric with the expanded diameter of the drum and provides a stop to center the segments and keep them concentric when they are expanded. The shaft drum core extension or stud 18 has slidably mounted thereon a segment expanding disc 30 formed with a rearwardly projecting centering sleeve or flange 30^a which engages about the stud 18. The outer portion of the disc 30 is formed with a flange 31 which engages a flange 31^a at the outer end of each segment to limit expansion of the segments. Attached to the rear face of the disc 30 is a segment collapsing ring 32 having a flange 32^a engageable with the extensions 29 on the segments 19. Keys 33 are provided between the surfaces 15, 15^a; 16, 16^a; and 17 and 17^a to prevent circumferential rotation of the segments 19 on the shaft drum core 1 but provide for longitudinal movement of the segments relative to the core or shaft 1.

Shaft-drum core 1; inner race of bearing 3; spacer sleeves 24 and 25; retaining collar 22; segment collapsing ring 23; keys 33 and segment collapsing disc 27 are all fixed as by screws, keys, welding or otherwise to each other so as to form one unitary structure. The movement of each segment 19 from a collapsed to an expanded position is indicated by the numeral 34. Expanding disc 30 and collapsing ring 32 are fixed together as by screws or other fastening means 30^b and are attached to rod 35 by fastening means 35^a. Rod 35 is slidable in the base of the drive shaft bore.

The operation of contracting the drum which in Figures 1 and 2 is shown expanded is as follows: Rod 35 is adapted to move expanding disc 30 with collapsing ring 32 forward or to the right in Figures 1 and 2, the ring 32 engaging the internal flange 29 of the segments 19 and moving

all of them longitudinally forward. The projecting tongues 26 which engage in the slots 28 of the collapsing disc 27, and the rear end frusto-conical surface 20 which engages collapsing ring 23, will effect inward movement of the segments 19 to a collapsed position coincident with the outward longitudinal movement of the segments.

To expand the drum, the longitudinal movement of the rod 35 is reversed. The segments will move rearwardly and outwardly on frusto-conical surfaces 15, 16 and 17, expanding the segments until segment extension 29 engages the rim extension 31 of expanding disc 30, and the outside segment surface engages cylindrical surface 20^b of the collapsing ring 23 both of which limit the expansion and provide a perfect concentric cylindrical drum.

To provide for the shorter periphery when the drum is collapsed, a telescopic joint is provided at the edges of the segments which are mortised with parallel tongue 19^a and groove 19^b as shown in Figure 10, or dovetail as shown at 19^c and 19^d in Figure 10A. The relative positions of the edges of the segments when they are expanded are more clearly shown in Figures 10 and 10A.

In order to provide a continuous cylindrical surface these grooves and gaps between the segments are covered by arch plates 207 of springy material (not shown in Figure 10 or 10A but similar to that shown at 207, Figure 7) curved to conform with the cylindrical surface of the drum and having one edge rigidly attached to one segment and made of such width that it spans the joint gaps and slidably engages on the adjoining segment but is unattached and has a beveled wedge-like edge 208. A corresponding bevel 208^a is formed on its supporting segment, and when the drum is collapsed, the periphery shortens and the bevel on the unattached end of the arch plate follows the correlated bevel 208^a on the segment and telescopes along its surface.

Longitudinal movement of rod 35 to effect collapsing and expanding of the drum is produced either hydraulically as shown in Figure 1 or by screw and nut which will be described later. Referring to Figure 1, a hydraulic rotating type cylinder 36 is screwed or otherwise rigidly attached to the rear end of the driving shaft 1 so its cylindrical axis coincides with the longitudinal axis of the shaft, drum and rod all of which are identical. A sleeve 37 is provided between the cylinder and the inner race of bearing 2 rigidly clamping it on shaft 1. As this bearing 2 is a combined radial and thrust bearing, it arrests any longitudinal movement of the shaft and drum, with any slight expansion provided for by roller bearing 3.

Cylinder 36 is provided with the usual stuffing box bush 38, packing 39, gland 40 and piston 41, rigidly attached to rod 35 which becomes the piston rod. Cylinder head 42 has attached the spindle or rotating plug 43 of the rotating joint connection through which liquid pressure is supplied to the cylinder. The longitudinal axis of this plug coincides with the axis of the cylinder 36 and drive shaft 1 and therefore there is no radial or longitudinal motion, only rotary. The body 44 of the rotary joint is held on the plug 43 by washer 45 with its necessary screws and cap 46 encloses these parts.

Body 44 has annular ports 47, 48 and 49. Annular port 47 coincides with port 50 in plug 43 and leads through the plug and the cylinder head 42 and through the side wall of cylinder 36 to the front end of the cylinder. Annular port 48 coincides with port 51 which leads through plug

43 to the rear end of the cylinder. Annular port 47 is connected to a four way valve 52 by pipe 53 and annular port 48 is connected by pipe 54.

Pipe 55 connects to the body of the rotating joint and drains any leakage which gathers in the space under cap 46 and pipe 56 connects to annular port 49 for the same purpose and drains into pipe 55. Liquid pressure is supplied to the four way valve through pipe 57 and exhausts through pipe 58. It is obvious that liquid pressure can be applied to or held in either end of the cylinder regardless of whether the cylinder shaft and drum are rotating or stationary.

As illustrated in Figures 1 and 2, the coiling drum is expanded and in Figure 1, the operating handle 59 of the four way valve 52 is admitting liquid pressure to the front end of cylinder 36 and exhausting it from the rear end; in position 60 the liquid is locked in both ends of the cylinder and holds the drum in whatever expanded or collapsed position it is when the valve is turned to this position, in position 61 liquid pressure is admitted to the rear end of cylinder 36 and the front end is exhausting thereby collapsing the drum.

Some engineers object to liquid pressure for operating equipment and to meet this objection I have devised a motor operated, magnetic clutch connected, collapsing-expanding mechanism as shown in Figure 4 and a similar arrangement except that the connection is made by a friction clutch as shown in Figure 5 with sections shown in Figures 8 and 9.

In Figures 4 and 5, the radial and thrust bearing 2, retainer 13 and partly shown drive frame 4, drive gear 5, and the balance of the drive (not shown) is the same as described in connection with Figure 1. The drive shaft-drum core 1 and rod 35 are identically the same from radial and thrust bearing 2 forward to the end of the coiling drum but to the rear of this bearing the shaft 1 and rod 35 are entirely different embodying a screw thread 70 on rod 35 and nut 71.

The sole object of this mechanism is to produce, independent of shaft 1 a power rotating means for screwing on and unscrewing of nut 71 on thread 70 of rod 35, which can be perfectly controlled and will produce positive longitudinal movement in either direction of rod 35 when it is at rest or rotating in either direction, also to arrest this movement at exactly the correct instant; the parts being arranged so the stress caused by a coil wound on the drum will be taken directly by shaft 1, rod 35 preferably in tension and nut 71, also so the nut rotating means will be completely disconnected from the nut and can remain inoperative while the coil is being formed.

In this mechanism the end of rod 35 extends beyond the end of shaft 1, the extension being threaded as at 70 and having a sleeve-like nut 71 with a corresponding thread, the outer end of the nut 71 abutting the rear end of shaft 1. The outer end of the nut is formed with a flange 71a and collar 72 encircling the end of and carried by shaft 1, the end of which is grooved to receive a split retaining collar 73 and a deeper groove for the bifurcated collar 74. On the opposite end of the nut 71 is screwed or otherwise attached the armature hub 75, armature spring plate 76 and magnet armature member 77 of a magnetic clutch. Hub 75 is prevented from rotating on nut 71 by key 78.

Other parts of the clutch consist of friction lining 79, magnet field member and hub 80 and magnetizing coil 81 which are rigidly keyed on shaft 82 of a combined motor and reduction gear

5 of which the gear box 83 is to reduce speed and increase power. The motor proper 84 which is preferably series wound has keyed on its armature shaft the brake drum 85 of a series brake which applies the brake shoes 86 with a spring and releases them by a magnet 87. Mounted on clutch magnet field member and hub 80 are two annular collector rings 88 and 89 insulated from the hub by sleeve 90.

In this description the word insulation or a derivative thereof will mean a non-conductor of electricity. Collector ring 88 is connected by a conductor 91 and ring 89 by conductor 92 to clutch magnetizing coil 81, all properly insulated. Brushes for these rings are identified by 93 and 94, respectively.

For arresting movement at the proper instant, I have devised a special limit switch for which there are provided two annular collector rings 95 and 96 mounted on nut 71 and insulated therefrom by sleeve 97. Also mounted on this sleeve is contact finger 98 connected to ring 96 also contact finger 99 connected to ring 95 by conductor 100. Brushes for rings 95 and 96 are indicated by 101 and 102, respectively. As several revolutions of nut 71 on screw thread 70 will be necessary to secure the desired longitudinal movement of rod 35, and to prevent the contact fingers 98 and 99 making connection after one revolution, there is provided a floating contact with wedge shaped ends 103 carried by insulation support 104 attached to floating or pilot nut 105 having a width of several times the movement desired in rod 35.

The outside diameter of nut flange 71a and collar 72 are somewhat larger than the outside diameter of retaining collar 73 and is provided with a thread 106 the same pitch and number of threads per inch as thread 70 on rod 35. The inside diameter of pilot nut 105 has a corresponding thread and the outside diameter has mounted thereon an insulation sleeve 107 and wide face annular collector ring 108, which is connected to floating contact 103 by a conductor 109 and is provided with brush 110.

Pilot nut 105 has an integral projecting pawl 111 considerably longer than the movement desired in rod 35 and is used to permit longitudinal movement but to restrain circumferential rotation of the pilot nut with relation to shaft 1, which is accomplished by the pawl 111 projecting through the bifurcation 74a on collar 74 which is made in halves and prevented from rotating on shaft 1 by dowel pin 112.

A sleeve 113 between the bifurcated collar 74 and inner race of radial and thrust bearing 2 rigidly clamps the inner race on shaft 1, arresting any longitudinal movement of the equipment. The longitudinal axes of all rotating parts are in line and they are therefore concentric with each other. Rod 35 has an integral key 114 which slides in keyway 115 in the hollow of shaft 1 and provides for limited longitudinal movement but prevents rotative motion with relation to shaft 1.

Shaft 1, inner race of bearing 2, sleeve 113, bifurcated collar 74 and dowel 112 are attached by various means to each other thereby forming an integral unit which is adapted to rotate as such. Nut 71, 72, retaining collar 73, hub 75, spring plate 76, magnet armature 77, key 78, collector rings 95 and 96, insulation sleeve 97, contact fingers 98 and 99, also connector 100, are attached to each other forming an integral unit and provides for rotation in either direction regardless 70 of whether shaft 1 is rotating or at rest.

Friction lining 79, magnet field member 80, magnetizing coil 81, collector rings 88 and 89, insulating sleeve 90, conductors 91 and 92 likewise are an integral unit and are rotated in either direction by shaft 82 of gearmotor 83, 84. There is no longitudinal movement in these last three integral units except that provided by armature spring plate 78 for armature member 77 in order to close the gap between itself and friction lining 79 which causes the magnetic clutch to function.

The last integral unit consists of contact 103, insulation support 104, pilot nut 105, insulation sleeve 107, collector ring 108, conductor 109, all of which are rotated identically with shaft 1 by pawl 111 and bifurcated collar 14. If there is no relative rotation between nut 71 and shaft 1, there is no longitudinal movement in either rod 35 or pilot nut 105. However, if nut 71 is rotated in either direction with relation to shaft 1, there is longitudinal movement of both rod 35 and pilot nut 105 and its attachments which is effected by their respective threads 78 and 106 also key 114 and pawl 111 preventing rotation of these parts with respect to shaft 1.

If it is deemed advisable nut 71 can be extended toward gearmotor shaft 82 and the shaft 82 extended through this nut extension and a bearing established to provide for centering and maintaining concentricity of these rotating parts.

The power rotating means to produce the independent relative rotary movement between shaft 1 and nut 71 is provided by the reversing combined gear and motor which is preferably series wound and it is connected and disconnected to the nut by the magnetic clutch, while the pilot nut 105, collector rings, contact fingers, etc., in conjunction with the gearmotor control provide the perfect control for the magnetic clutch-connected, collapsing and expanding mechanism.

A manually operated controller is perfectly satisfactory for controlling this mechanism and the wiring diagram illustrated in Figure 4 is the well-known reversing drum type and provides for clockwise and counterclockwise rotation from a neutral position. Under the words counterclockwise and clockwise are a series of numbers 1 to 5 with corresponding light vertical lines, which represent the number of resistance steps in the controller. The wide and narrow rectangles 120 to 126 through which these vertical lines pass represent the various movable contact segments for cutting out the resistance or connecting the armature, brake, magnetic clutch, special limit switches, etc., in the circuit.

The heavy vertical and horizontal lines are conductors which join the contact segments making practically one conductor out of each group of contact segments. These segments are actually mounted on a cylindrical drum but for ease of explanation are indicated in the diagram as if the cylindrical surface were unrolled and laid on a flat surface.

The contacts A, B, C, D, E, F, L, R1, R2, R3, R4, R5 and S1, S2, S3 represent fixed contact fingers which can be connected to each other by means of the movable contact segments on the drum of the controller. The heavy lines 127 at the right of and connected with R1 to R5 is the starting resistance in the circuit. The series brake, series field, armature, blow out coils and electric supply are so marked. The magnetic contactor 128 is a switch which is normally closed, its contacts 129 are opened when a current passes through its electro-magnet 130.

In Figure 4, the mechanism is shown at rest in the position it occupies immediately after the colling drum has been collapsed, the magnetic clutch is disconnected and the drum of the controller is in its neutral position. Rod 35 is in the extreme forward position and it is desired to expand the drum or move rod 35 longitudinally toward the gearmotor 84.

The operation of the control and other mechanism is as follows. Thread 78 on rod 35 being right hand, nut 71 must rotate counterclockwise when looking from the front end. The electric supply passes through main switch 131 to terminals 132 and 133. No current is flowing as no circuit is complete. Counterclockwise segments are now rotated bringing segments 120, 121, 122 and 123 in contact with their respective contact fingers. Current now flows from switch terminal 132 through conductor 134 to contact finger L 20 through segments 121 to R1 through the resistance 127.

Continued rotation of the controller drum successively eliminates resistance 127 as the movable segments 121 contact the fingers R2, R3, R4 and 25 R5 when full current passes through the circuit of conductor 135, 136 through magnet 87 of series brake releasing it, conductor 137 through series field, conductor 138 to contact finger E, segments 122 to D, to C, conductor 139 through armature, 30 conductor 140 to contact finger A, segments 123 to B, conductor 141, blow out coils, conductor 142, joining conductor 143, through magnetic contactor 128, contacts 129 normally closed, conductor 144 to main switch terminal 133 completing the 35 circuit and rotating the motor as well as the magnetic clutch members counterclockwise.

Where conductor 135 joins 136 the circuit divides, part going through conductor 145, brush 84, collector ring 88, conductor 82, through magnetizing coil 81 of magnetic clutch, conductor 81, collector ring 88, brush 88. Conductor 146 joining conductor 143 completes the magnetic clutch circuit through 128, 129 and 144 to main switch terminal 133.

45 The circuit for the magnetic clutch having been completed, the armature 77 is drawn in contact with the rotating friction lining 79 causing the armature 77 and nut 71 with its attachments to rotate counterclockwise, while shaft 1, rod 35 and pilot nut 105 are at rest causing both rod and nut to move toward the gearmotor and thus expanding the drum. The movement of rod 35 and pilot nut 105 continues until contact finger 88 which is rotating, and floating contact 103 which is moving in the direction of finger 88, come in to engagement with each other.

Current will then flow in the limit switch circuit from resistance 127 through conductor 147, brush 110, collector ring 108, conductor 109, floating contact 103, finger 88, collector ring 86, brush 102, conductor 148 to contact finger S3, segments 120, contact finger S2, conductor 149, electromagnet 130 of magnetic contactor 128 (normally closed), conductor 150, joining conductor 144, to main switch terminal 133, completing the limit switch circuit and resulting in current flowing through the electromagnet 130 of the magnet contactor, thus opening the contacts 129, which 65 breaks the main line circuit and disconnects the magnetic clutch, gearmotor and series brake, the spring of which now sets the brake.

Figure 5 shows rod 35, pilot nut 105, floating contact 103, contacting finger 88 in the position 75 just described with reference to Figure 4 when

the coiling drum becomes fully expanded. From this expanded position it is next desired to collapse the coiling drum, which is accomplished by rotating the controller drum in the opposite direction until the clockwise movable segments 124, 121, 125 and 126 engage their respective contact fingers and controller rotation is continued eliminating all resistance 127 as previously described.

The flow of current for clockwise rotation is through the following conductors, fingers, segments, etc., forming the circuits from the main switch 131. The gear motor circuit starting at switch terminal 132 passes through 134, L, 121, R1, R2, R3, R4, R5, 135, 136, 87, series brake releasing it, 137, series field, 138, E, 125, F, 140, armature, 139, C, 126, B, 141, blow-out coils, 142, 143, 128, 129, 144 to 133 main switch terminal causing clockwise rotation of motor and magnet field member of magnetic clutch.

The circuit for this clutch is the same as before starting at conductor 135 where it joins 136 through 145, 94, 89, 92, 81, 91, 88, 93, 149, 143, 128, 129, 144 to switch terminal 133 completing the circuit, and energizing the magnetic clutch and connecting it with its armature 77 and nut 71 with its attachments as previously described except that the rotation is in the opposite direction or clockwise, moving rod 35 forward or away from the gearmotor 84 which collapses the coiling drum.

Screw rod 35 and pilot nut 105 with their attachments start the collapsing operation from the position shown in Figure 5 and complete it when the positions shown in Figure 4 are reached, when the circuits must be broken. This is effected by current passing through the limit switch circuit from resistance 127 to conductor 147, 110, 108, 109, 103, 99, 100, 85, 101, 151, S1, 124, S2, 149, 130, 150, 144, to switch terminal 133. This closes the limit switch circuit and energizes electro-magnet 130 of magnetic contactor 128 (normally closed), which opens the contacts 129 and breaks the main line circuit disconnecting the electrical equipment. The brake spring thereafter applies the brake, all as described with the counterclockwise rotation.

Figure 5 also shows a collapsing expanding mechanism in which the connection between the gearmotor and nut 71 is effected by a friction type of clutch. In this arrangement the shaft 1, rod 35, pilot nut 105 and drive frame 4 with all their attached parts are identically the same as Figure 4. Nut 71 and all its attachments are the same except that armature hub 75, spring plate 76 and magnet armature member 77 are replaced by the cup-shaped clutch member 170 of a cone type friction clutch with hub cast integral and screwed or otherwise attached to nut 71 with key 18 preventing rotation on nut 71.

The gearmotor unit is the same except that it has a longer shaft 171 to provide a mount for a friction clutch cone member 172 with friction lining 173. A hub 174 is carried by the clutch member 172 and is provided with a groove 174* for a trunnioned shifting yoke 175. Hub 174 has a sliding fit on shaft 171 being splined on this shaft to prevent rotation of the hub on the shaft. A bifurcated shifting lever 176 is connected to the trunnions 175* of shifting yoke 175 and is pivotally mounted as at 177 on the motor base 178. The operating end of the lever is connected at 179 to a piston rod 180 connected to a piston 181 which is slidable in a double acting pressure cylinder 182 of usual design, thus providing means to shift the cone 172 for connecting and disconnecting the

gear motor with nut 71 through the friction clutch.

Pressure for operating cylinder 182 is supplied through pipes 183 and 184 by a solenoid controlled four way piston valve. The body of the valve is designated 185 and the slide valve is designated 186. The valve 186 is moved longitudinally of the body 185 by solenoids 187 and 188, each solenoid when energized pulling the valve 186 in one direction. The fluid pressure for the cylinder 182 is supplied through pipe 189 and exhausts through pipe 190. Pressure port 191 communicates with pipe 183 and pressure port 192 communicates with pipe 184 and exhaust port 183 communicates with the exhaust pipe 190.

The control for the gearmotor and series brake are identically the same as shown in Figure 4 with the magnetic clutch circuit omitted. For controlling the solenoids on the four way valve 20 and limit switch circuit, a slight change is necessary necessitating the addition of two movable contact segments 123A and 126A, also fixed contact finger X. Inserted in the limit switch circuit is a magnetic contactor 152 which constitutes 25 a switch whose contacts 152A are normally open but are closed when a current passes through its electro-magnet 153, one end of which is connected to contact finger S2 and the other end to conductor 154 connecting to the electro-magnet 30 130 of magnetic contactor 128.

Conductor 155 connects contacts 152A of the magnetic contactor 152 with conductor 154. Solenoid 187 is connected to conductor 135 by conductor 156 and to contact finger X by conductor 157. Solenoid 188 is connected to conductor 147 by conductor 158 and by 159 to contacts 152A of magnetic contactor 152.

In Figure 5, the mechanism is shown at rest in the position it occupies immediately after the 40 coiling drum has been expanded with the friction clutch disconnected and the drum of the controller in its neutral position. To collapse the coiling drum rod 35 must move forward or away from gear motor 84. Thread 78 being right hand, 45 clockwise rotation when looking from the front end of nut 71 will produce the desired movement in rod 35.

The circuits of the control and operation of the other mechanism is as follows: the electric 50 supply passes through main switch 131 to terminals 132 and 133 but no current is flowing as there are no completed circuits. The controller drum is now rotated so the clockwise movable segments 124, 121, 125, 128 and 126A come in 55 contact with their respective contact fingers which completes the circuits and current flows from switch terminal 132 through conductor 134 to contact finger L, segments 121, R1 and through the starting resistance 127.

Continued rotation of the controller drum successively eliminates resistance 127 as the movable segments 121, contact fingers R2, R3, R4 and R5 when full current passes through the circuit of conductor 135 to magnet 87 of series brake releasing it, conductor 137, series field, conductor 138 to finger E, segment 125, finger F, conductor 140, armature, conductor 139, finger C, segment 128, finger B, conductor 141, blow out coils, conductor 142 to contacts 129 to magnetic contactor 128 70 (normally closed), conductor 144 to terminal 133 of switch 131, completing the circuit and rotating gear motor clockwise.

The circuit for valve solenoid 187 is from conductor 135 through conductor 156 through the 75 solenoid 187, conductor 157 to finger X, segments

126A to 126 to finger B connecting to the main circuit through conductor 141 and energizing solenoid 187 which pulls the piston valve from the position shown at 186 to position shown at 183a in Figure 5A.

Fluid pressure from supply pipe 189 now flows through the right hand annular groove 186b in valve piston in position 186a to pressure port 192 to pipe 184 and cylinder 182 pushing piston 181 and rod 180 connected at 179 to bifurcated lever 176 until they arrive at position 176A and 179A shown in dotted lines. This shifts the friction clutch cone member 172 in contact with its cup member 170, imparting to it and nut 171 the same rotary motion as that produced by gearmotor which is clockwise as desired, moving rod 35 forward and collapsing the coiling drum, and at the same time moving pilot nut 105 with its attachments and floating contact 103 in the same longitudinal direction.

The opposite or stuffing box end of cylinder 182 exhausts through pipe 183 pressure port 191 left hand annular port 186c of piston valve in position 186a to exhaust port 193 and to exhaust pipe 190. Clockwise rotation of nut 71 and forward longitudinal movement of rod 35 and pilot nut 105 continue until floating contact 103 engages contact finger 99 (as shown in Figure 4) of the limit switch circuit. This circuit is as follows: from resistance 127 to conductor 147 to brush 110, collector ring 108, conductor 109, floating contact 103, finger 99, conductor 109, ring 95, brush 101, conductor 151 to finger S1, segments 124, finger S2, to electromagnet 153 of magnetic contactor 152 (normally open), conductor 154 to electromagnet 130 of magnetic contactor 128, (normally open), to conductor 159, conductor 144, to switch terminal 133, which completes the limit switch circuit, energizing electromagnet 130 of magnet contactor 128 and opening contacts 129, thus breaking the main circuit which disconnects and renders inoperative solenoid 187, gearmotor 84 and magnet 87 of series brake, the spring of which now sets the brake and arrests rotation.

On completion of the limit switch circuit, current energized the electro-magnet 153 of magnetic contactor 152, closing the contacts 152A (normally open) which completed the circuit for solenoid 188 beginning at conductor 147 through conductor 158 through solenoid 188 conductor 159 to contacts 152A which are now closed, conductor 155, conductor 154 completing the circuit through 130, 150, 144 to switch terminal 133. This energizes solenoid 188 and pulls valve piston from position 186a to position 186 when pressure from supply pipe 189 flows through the left hand annular groove in valve piston 186 to pressure port 191 through pipe 183 into cylinder 182 thus moving piston 181, piston rod 180, lever connection 179 and lever 176 from position shown by dotted lines 176A and 179A to the full line position shown thus disconnecting the clutch 170, 172.

The opposite end of the cylinder 182 exhausts through pipe 184 pressure port 192 right hand annular groove 186b in valve piston to exhaust port 193 and to exhaust pipe 190. After these operations are completed the drum of the controller is returned to its neutral position.

To expand the coiler drum the drum of the controller is rotated so the counterclockwise movable segments 120, 121, 122, 123 and 123A engage their respective contact fingers and controller rotation is continued eliminating resist-

ance 127 as previously described. The flow of current for counterclockwise rotation is through the following segments, fingers, conductors, etc., forming the circuits from the main switch 131.

5 The gearmotor circuit starting at switch terminal 132 passes through 134, L, 121, R1, R2, R3, R4, R5, 135 magnet 87 of series brake releasing it, 137, series field, 138, E, 122 D, C, 139 armature, 140, A, 123, B, 141 blowout coils 142, 128, 129, 144, 133 switch terminal completing the circuit and producing counterclockwise rotation.

The circuit for solenoid 187 branches off of conductor 135 through 156, 187, 157, X, 123A, 123, B, 141, blow out coils, 142, 128, 129, 144, 133 switch terminal completing the circuit and operating solenoid 187, valve piston 186, cylinder 182, etc., exactly the same as described for clockwise rotation.

The limit switch circuit starts from resistance 20 127 to 147, 110, 108, 109, 103, 98, 96, 102, 148, S3, 120, S2, 153, 154, 133, 150, 144 to 133 the switch terminal completing the limit switch circuit and closing the circuit for solenoid 188, through conductors 158, 188, 159, contacts 152A now closed, 25 152, 155, 154, 130, 150, 144 to 133 the switch terminal. This again operates solenoid 188, valve piston 186, cylinder 182 etc., exactly the same as described for clockwise rotation.

I have described and illustrated the simplest 30 type of friction clutch, but the collapsing expanding mechanism and control as described is equally adaptable for use with any type of friction clutch, single or multiple disc, expanding or contracting band, gear or jaw clutches and any other type of rotary drive may be substituted for the gearmotor.

To simplify the description of this collapsing-expanding mechanism I have started it "at rest" but it is obvious the equipment will work equally well if rotating in either direction or at rest.

The coiling drum and its auxiliary operating equipment as described is not provided with a gripping device to hold and carry the leading end of the strip around the drum to form the first 45 convolutions of the coil, and it is, therefore, necessary to provide the familiar "belt-wrapper" to accomplish this result.

A belt-wrapper is an endless belt threaded over stationary and hinged rollers carried in a frame 50 mounted on a carriage movable transversely with relation to the coiling drum axis. To form the first few coil convolutions on the empty coiler drum the belt-wrapper is advanced toward the drum, the belt first engaging the drum then the hinged roller swings up so approximately three quarters of the drum is tightly encircled by the belt which, due to the friction against the drum, is traveling at the same surface speed.

The strip is led in through the one-quarter 55 open space not encircled by the belt and fed between it and the rotating drum, which carries the leading end of the strip around the tightly encircled portion of the drum, and under the on-coming strip thus forming the first convolution.

60 After several convolutions are formed the belt-wrapper is withdrawn to make room for the progressively increasing coil. Patent 2,172,616 clearly illustrates this belt-wrapper device as now used which is a modification of Patent 1,230,750.

65 It is obvious that several operations are necessary to engage and disengage the coiling drum and belt-wrapper, which is large and cumbersome occupying a large amount of floor space, and it is also expensive. To eliminate the cost of this belt-wrapper with its several necessary opera-

tions, also the floor obstruction which it causes, I have devised means consisting of electromagnets imbedded in the coiling drum segments and arranged to attach by magnetic attraction the leading end of the strip to the coiler drum, carrying it around the drum as it revolves, thus forming the first convolution of the coil.

The arrangement of the electro-magnetic coils in the drum segments of the collapsing-expanding drum is shown most clearly in Figures 2, 6, 7 and 10. The segments, which are made of highly magnetizable material, are provided on their outer surface with an even number of longitudinal slots or grooves 200 with arcuate (or rectangular) ends 201 connecting each pair. The size, depth and number of grooves will be determined by the material to be coiled, and they provide the space into which the electro-magnet coils 202 are embedded, somewhat similar to the winding of a motor armature.

The electro-magnetic coils in each segment are connected to each other and have an inlet conductor 203 and a duplicate outlet conductor 204 (shown only in Fig. 10). Inlet conductor 203 terminates in contact 205 and is insulated from the segments 19 by a non-conductor sleeve 206 (see Figure 3). These electro-magnetic coils must be protected from damage, and the grooves as well as the telescopic joint between the segments must be arched over to present a smooth continuous cylindrical surface so the highly finished strip surface is not damaged, which would impair its commercial value.

This is accomplished with arch plates 207 covering the grooves 200 also the joints between the segments. Arch plates 207 (Figure 7 (removed in Figure 10)) are of non-magnetic springy material curved to conform with the cylindrical surface of the drum and having one edge rigidly attached to one of the segments and arching over one or more of the grooves 200 in which the electro-magnetic coils 202 are embedded, thus protecting them. The arch plate 207 is of such width that it also spans the joint gaps between adjacent segments and is supported on the adjoining segment, but is not attached to it, having a beveled wedge-like edge 208 with a correlated bevel 208^a on the supporting segment.

The balance of the longitudinal grooves 200 are dovetailed at their outer edges and non-magnetic arch strips 209 are forced longitudinally into these dovetails. The arcuate (or rectangular) end grooves 201 are covered by non-magnetic plates or sleeve forming segments 210 at the front end and 211 at the rear end divided into the same number of segments as the drum and having a width great enough to cover the arcuate end grooves 201 and a part of its longitudinal connecting groove 200. The longitudinal edges of plates 210 and 211 are beveled at 208 and they form a continuation of the unattached edge of arch plate 207.

The balance of sleeve forming segments 210 and 211 are firmly attached to the drum segments 19, and the attached end is beveled the same as and forms a continuation of the bevel 208^a on the drum segment. The length of arch plate 207 and arch strip 209 will extend longitudinally from sleeves 210 to sleeves 211. When the drum is collapsed the periphery shortens and the bevel 208 on the unattached end of the arch plates 207 and sleeve segments 210 and 211 follows the correlated bevel 208^a on the drum segments 19, and bevel continuation on the attached ends of sleeve segments 210 and 211 and tele-

scopes along the drum surface, reducing the drum diameter and permitting removal of the coil.

To satisfy the requirements in some cases the entire surface of each drum segment can be covered by one piece of non-magnetic material in lieu of strips and plates as described. To supply electric current to the electro-magnetic coils an extendible contact as shown in larger scale at Figure 3 is provided consisting of an extending telescoping tubular conductor finger 212 sliding in a conductor sleeve 213 and both provided with shoulders 212^a and 213^a respectively to prevent dis-assembly.

Conductor sleeve 213 is provided with an outer annular collar 213^b near its longitudinal center to position itself against insulating collared bushings 214 and 215 all of which are clamped and held rigidly in retaining collar 22 by a nut 216 threaded into collar 22. The rear end of sleeve 213 is internally threaded for conductor plug 217 which is also the seat for compression spring 218 which tends to extend finger 212 and always keep it in contact with terminal 205. Two of these extendible contacts are provided for each drum segment and they are so disposed in retaining collar 22 that their longitudinal center line coincides with the center line of terminal contact 205, both of which are disposed at the same angle with relation to the coiling drum axis as the frusto-conical surfaces.

It is obvious that the short longitudinal movement required to collapse the drum segments 19 will not change the center line coincidence of finger 212 and terminal 205, and they will always be in contact. Attached to the rear surface of retaining collar 22 is a disk of insulating material 219 (Figure 2) on which are mounted two annular collector rings 220 and 221.

Conductor 222 connects collector ring 221 to conductor plug 217 of extendible contact connecting with one of the terminals 205 of each drum segment. The other terminals of each drum segment connect in a similar manner (not shown) to collector ring 220. Attached to the drive frame 4 is a piece of insulating material 223 on which are mounted two brush holders 224 and 225 each provided with their tension springs and brushes contacting collector rings 220 and 221.

The operation of the magnetic coiling drum is as follows: The drum is expanded, the electric supply passes through control switch 226 to its terminal 227, conductor 229 to brush holder 224 and through its brush to collector ring 221, through conductor 222 to extendible contacts 217, 218, 213 and 212, to contact terminals 205 of each segment, through the electro-magnetic coils, and returning in a similar manner from each segment to collector ring 220, brush and brush holder 225, conductor 230, to terminal 228 of control switch 226, completing the circuit and energizing the electro-magnetic coils, and converting the entire surface of the drum into a magnet to which the leading end of the strip will adhere and be carried around the drum as it revolves, thus forming the first convolution of the coil without any interruption of operations, the coiling continuing until the coil is complete.

As the strip leaves the mill it passes over its regular guides onto the magnetic coiling drum without its flow line being diverted, and no manual manipulation is necessary, thus avoiding extended or telescoped convolutions which usually occur when the leading end of the strip has to be

entered manually in a gripper slot. It is obvious that this magnetic coiling drum eliminates the belt-wrapper.

As the leading end of the strip will be attached to the magnetic coiling drum equally well while it is rotating or when it is at rest it is obvious that it is not necessary to stop the mill or any other equipment preceding the magnetic coiling drum, as is the case when the drum is provided with a gripper to hold the leading end of the strip. After the coil is completed the drum is collapsed as previously described and the coil is removed by my magnetic coil stripper Patent #2,198,644, or any other means, after which the drum is expanded as previously described and is ready to form the next coil.

In the various figures illustrating the collapsible-expanding coiling drum, only three frusto-conical surfaces are shown, but it is obvious that the number can be reduced to two for very short drums or increased to any desired number for long drums. It is also obvious that the angle of the frusto-conical surfaces with relation to their axes can be increased or decreased as desired, thus regulating the tension in and size of the rod 35 which imparts the longitudinal movement to the segments to produce the collapse of also expansion of the drum.

It is also obvious that the face width of the frusto-conical surfaces can be increased or decreased as desired, which, in conjunction with the number of these surfaces provided, will regulate and reduce to a safe margin the unit contact pressure between the drum core and the segments, which is impossible in drums using rollers, cams, etc.

While only the frusto-conical surface for collapsing and expanding the segments has been described, it is obvious that the same results can be attained with frusto-pyramidal surfaces.

While the foregoing descriptions referred to magnetic collapsible expanding drums in connection with reducing mills, it is obvious that they are equally adaptable to any processing equipment requiring coiling of the strip, after the processing operation, and they are particularly adaptable for coiling narrow strips which have been slit from a wider strip by a rotary slitting shear in a slitting line. With the known method it is impossible to enter a number of strips in the drum gripper and at the same time keep them central, in line, and with the same tension in each strip.

With the known type of coiling drums coiling several narrow strips side by side, which were slit from a wider strip, it is necessary to stop all operations and to manually enter each narrow strip in a gripper slot, which necessitates holding each and every one of the narrow strips in the gripper while the succeeding narrow strip is entered before the gripper can be closed to grip the strips, after which the slitting and coiling proceeds. This manual handling of the individual narrow strips diverts them from their path of flow between the slitting shear and coiling drum causing crooked entry of the strip in the gripper, and some of the strips are entered deeper in the gripper than others causing different tension in the various strips. All of these difficulties make it impossible to secure a uniform coil.

With the magnetic drums the narrow strips pass side by side from the slitting shear in their regular path of flow onto the magnetic coiling drum, without any manual handling or manipulation, and adhere to it and are carried around

the drum as it revolves for the first convolution of the coil without interruption of operations, and a perfect coil is formed from each strip.

If for any reason the narrow strips are diverted from their path they can be quickly aligned by stopping the slitting shear and preceding equipment as soon as any of the leading ends of the strips adhere to the magnetic drum, and continuing rotation of the drum. The strips being held stationary by the preceding equipment will cause the strip to slip on the drum while it is rotating, this producing equal tension in all strips. If they are out of line there will be more tension in one side of the strip than in the other and as the slippage of the strip on the rotating drum equalizes the tension in both sides of the strip, it will gradually shift sideways on the drum until they are in line, when all equipment can proceed and a perfect, uniform coil from each strip will result.

While these drums are primarily for coiling strip, they are also adaptable to use as an uncoiler in which case the operations are reversed, viz., the drum is collapsed, the coil is placed at the end of the drum so the axis of its hollow center coincides with the drum axis. The coil is then pushed on the drum and the segments expanded holding the coil firmly when the uncoiling can proceed.

It is obvious that the objects of this invention as previously stated will be accomplished by the equipment described.

Certain preferred features of the invention have been herein illustrated and described, it will be understood, however, that changes in the construction and operation of the parts may be made without departing either from the true spirit or scope of the invention. These variations are to be determined from the appended claims.

What I claim is:

1. In a sheet rolling mill or other processing equipment, a sheet winding means comprising a rotatable overhung shaft and a collapsible drum carried by said shaft, said drum including a plurality of arcuate members loosely carried by said shaft, means at each end of said members holding said members on said shaft for movement relative to said shaft, correlated means carried by said shaft, said members and said holding means for effecting radial movement of said members simultaneous with longitudinal movement, means at one end of said shaft engaging the adjacent ends of said members for shifting said members longitudinally of said shaft, operating means for said shifting means at the other end of said shaft, and a connecting means extending axially through said shaft connecting said operating means with said shifting means.

2. In a sheet rolling mill or other processing equipment, a sheet winding means including a rotatable shaft, means rotatably supporting said shaft with an end thereof in an extended position, the extended portion of said shaft having a plurality of collared frusto-conical surfaces, a plurality of transversely arcuate drum forming segments formed with concave frusto-conical surfaces on the interior thereof slidably engaging said collared surfaces, a disc formed with tapering annular shaped slots fixed to said shaft near the extended end thereof, transversely arcuate projections carried by said segments slidably engaging in said slots, an outwardly inclined extension carried by the opposite end of each segment, a collar fixed to said shaft having an annular recess in one face thereof in which said extensions

slidably extend, a ring fixed to said collar having a cylindrical and an internal frusto-conical bore in which said inclined extensions slidably engage, said ring and disc jointly holding said segments on said shaft and radially contracting said segments upon endwise movement of said segments in one direction with relation to said shaft and means engaging through said shaft connected with said segments for moving said segments endwise.

3. In a sheet rolling mill or other processing equipment a sheet winding means comprising a rotatable winding shaft, means supporting said shaft for rotation, said supporting means engaging said shaft adjacent one end and at an intermediate point to thereby dispose the opposite end of said shaft in projecting relation from said supporting means, said projecting portion of said shaft having a plurality of collared frusto-conical surfaces, a cylindrical drum including a plurality of transversely arcuate drum forming segments having interior complementary concave frusto-conical surfaces engageable with said collared surfaces for radially expanding said segments upon endwise movement in one direction thereof with relation to said shaft, means holding said segments on said shaft against rotary movement relative to said shaft while permitting endwise movement thereof, an axially shiftable disc member slidably carried by said shaft and engaging the adjacent ends of the segments for effecting endwise movement of said segments in both directions relative to said shaft, and operating means fixed to said disc member and extending axially through said shaft.

4. In a sheet rolling mill or other processing equipment, a sheet winding means comprising a rotatable winding shaft, means supporting said shaft for rotation, said supporting means engaging said shaft adjacent one end and at an intermediate point to thereby dispose the opposite end of said shaft in projecting relation from said supporting means, a collapsible cylindrical drum on the projecting portion of said shaft, said drum including a plurality of segmental members, complementary means carried partly by said shaft and partly by said segmental members for effecting radial movement simultaneous with longitudinal shifting of said segmental members, a disc disposed near the projecting end of said shaft and said segmental members, a collar fixed to said shaft adjacent the opposite end of said segmental members, a ring carried by said collar, said disc, collar and ring effecting radial contracting of said segmental members on endwise movement thereof in one direction with relation to said shaft, an axially shiftable disc on the projecting end of said shaft engaging the adjacent ends of said segmental members for communicating endwise movement in both directions thereto, said disc including means for limiting expansion of and maintaining concentricity of the adjacent ends of the segmental members, the expansion of the opposite ends of said segments being limited by the cylindrical bore of said ring, said ring and collar also maintaining said opposite ends of said segmental members concentric to said shaft, operating means for producing endwise movement of said segmental members engaging said shaft at the supported end thereof, and a rod connecting said operating means to said axially shiftable disc, said connecting rod extending axially through said shaft.

5. In a sheet rolling mill or other processing equipment, a sheet winding means including a ro-

tatable shaft, means rotatably supporting said shaft with an end thereof in an extended position, a collapsible drum on the extended end of said shaft, said drum including a plurality of arcuate segments, said shaft and segments having complementary inclined surfaces, said surfaces being angularly inclined toward the shaft axis to effect radial expansion and contraction of the segments simultaneous with longitudinal movement thereof with relation to said shaft, shifting means carried by said shaft engaging adjacent ends of said segments for effecting longitudinal movement of said segments, said segments being provided on both longitudinal edges thereof with interengaging means providing for reduced periphery when said segments are contracted, a springy arcuate plate attached to each segment overlapping said interengaging means whereby to form a smooth exterior surface when expanded, each plate slidably engaging over an adjoining segment, operating means mounted on the supported end of said shaft for producing longitudinal movement of segments, rod connecting means for communicating the longitudinal movement of said operating means to said segment shifting means, said connecting means extending axially through said shaft.

6. In a sheet rolling mill or other processing equipment, a sheet winding means comprising a sheet winding shaft, a plurality of drum forming segments on said shaft, means movably mounting said segments for combined radial and longitudinal movement, a rod loosely mounted axially in said shaft, a segment shifting member attached to one end of said rod, a rod shifting means rotatably carried by said shaft and threaded onto said rod, and means for rotating said rod shifting means to thereby shift said segments from a collapsed to an expanded position.

7. In a sheet rolling mill or other processing equipment, a sheet winding means comprising a sheet winding shaft, a plurality of drum forming segments on said shaft, means movably mounting said segments for combined radial and longitudinal movement, a rod loosely mounted axially in said shaft, a segment shifting member attached to one end of said rod, a rod shifting means rotatably carried by said shaft and threaded onto said rod, said rod shifting means including a clutch element threaded onto said rod, a second clutch element correlated with said first clutch element, and means for shifting one of said clutch elements relative to the other element.

8. In a sheet rolling mill or other processing equipment, a sheet winding means comprising a sheet winding shaft, a plurality of drum forming segments on said shaft, means movably mounting said segments for combined radial and longitudinal movement, a rod loosely mounted axially in said shaft, a segment shifting member attached to one end of said rod, a rod shifting means rotatably carried by said shaft and threaded onto said rod, and means for rotating said rod shifting means including complementary clutch elements and operating means connected with said elements.

9. In a sheet rolling mill or other processing equipment, a sheet winding means comprising a sheet winding shaft, a plurality of drum forming segments on said shaft, means movably mounting said segments for combined radial and longitudinal movement, a rod loosely mounted axially in said shaft, a segment shifting member attached to one end of said rod, a rod shifting

means rotatably carried by said shaft and threaded onto said rod, means for rotating said rod shifting means including driving means, electromagnetic clutching means, and operating means connected with said clutching means for coupling said driving means with said rod shifting means.

10. In a sheet rolling mill or other processing equipment, a sheet winding means comprising a sheet winding shaft, a plurality of drum forming segments on said shaft, means movably mounting said segments for combined radial and longitudinal movement, a rod loosely mounted axially in said shaft, a segment shifting member attached to one end of said rod, a rod shifting means rotatably carried by said shaft and threaded onto said rod, reversible means for rotating said rod shifting means including electromagnetic clutching means and reversible driving means connected with said clutching means.

11. In a sheet rolling mill or other processing equipment, a sheet winding means comprising a sheet winding shaft, a plurality of drum forming segments on said shaft, means movably mounting said segments for combined radial and longitudinal movement, a rod loosely mounted axially in said shaft, a segment shifting member attached to one end of said rod, a rod shifting means rotatably carried by said shaft and threaded onto said rod, a reversible electric motor for rotating said rod shifting means, electromagnetic clutching means for coupling said motor with said rod shifting means, and means operatively connected with said motor and said clutching means for limiting the shifting of said rod.

12. In a sheet rolling mill or other processing equipment, a sheet winding shaft, a plurality of drum forming segments on said shaft, means movably mounting said segments for combined radial and longitudinal movement, a rod loosely mounted axially in said shaft, a segment shifting member attached to one end of said rod, a rod shifting means rotatably carried by said shaft and threaded onto said rod, means for rotating said rod shifting means including a clutch element carried by said rod shifting means, a second clutch element, and fluid actuated means for shifting one element relative to the other element.

13. In a sheet rolling mill or other processing equipment, a sheet winding means comprising a sheet winding shaft, a plurality of drum forming segments on said shaft, means movably mounting said segments for combined radial and longitudinal movement, a rod loosely mounted axially in said shaft, a segment shifting member attached to one end of said rod, a rod shifting means rotatably carried by said shaft and threaded onto said rod, means for rotating said rod shifting means including a clutch element carried by said rod shifting means, a second clutch element, fluid actuated means connected with said second clutch element for shifting said second element relative to said first element, and electro-magnetic controlling means for said fluid actuated means.

14. In a sheet rolling mill or other processing equipment, a sheet winding means comprising a sheet winding shaft, a plurality of drum forming segments on said shaft, means movably mounting said segments for combined radial and longitudinal movement, a rod loosely mounted axially in said shaft, a segment shifting member attached to one end of said rod, a rod shifting

means rotatably carried by said shaft and threaded onto said rod, means for rotating said rod shifting means to thereby shift said segments from a collapsed to an expanded position, and coacting means carried by said rod and said shaft for holding said rod against rotary movement relative to said shaft while permitting longitudinal movement of said rod.

15. In a sheet rolling mill or other processing equipment, a sheet winding means comprising a sheet winding shaft, a plurality of drum forming segments on said shaft, means movably mounting said segments for combined radial and longitudinal movement, a rod loosely mounted axially in said shaft, a segment shifting member attached to one end of said rod, a rod shifting means rotatably carried by said shaft and threaded onto said rod, and means for rotating said shifting member, said rod and shifting member being so disposed relative to said shaft that all stresses tending to collapse or expand said segments are absorbed longitudinally by said shaft with said segments and rod shifting means moving as a unit.

16. In a sheet rolling mill or other processing equipment, a sheet winding means comprising a sheet winding shaft, a plurality of drum forming segments on said shaft, means movably mounting said segments for combined radial and longitudinal movement relative to said shaft, a rod loosely mounted axially in said shaft, a segment shifting member attached to one end of said rod, a rod shifting means rotatably carried by said shaft and threaded onto said rod, electric operating means for rotating said rod shifting means independently of the rotation of said shaft to thereby shift said segments from a collapsed to an expanded position, coacting means carried by said rod and said shaft for holding said rod against rotary movement relative to said shaft while permitting longitudinal movement of said rod, an electric control means for said operating means, and circuit making and breaking means connected with said control means carried by said rod shifting means and movable lengthwise of said shifting means for limiting the endwise movement of said rod.

17. In a sheet rolling mill or other processing equipment, a sheet winding means comprising a sheet winding shaft, a plurality of drum forming segments on said shaft, means movably mounting said segments for combined radial and longitudinal movement relative to said shaft, a rod loosely mounted axially in said shaft, a segment shifting member attached to one end of said rod, a rod shifting means rotatably carried by said shaft and threaded onto said rod, electric operating means for rotating said rod shifting means independently of the rotation of said shaft to thereby shift said segments from a collapsed to an expanded position, coacting means carried by said rod and said shaft for holding said rod against rotary movement relative to said shaft while permitting longitudinal movement of said rod, an electric control means for said operating means, said operating means including electro-magnetic clutching means connected with said control means and said rod shifting means, said control means including circuit making and breaking means operatively connected with said rod shifting means for limiting the endwise movement of said rod.

18. In a sheet rolling mill or other processing equipment, a sheet winding means comprising a sheet winding shaft, a plurality of drum forming

segments on said shaft, means movably mounting said segments for combined radial and longitudinal movement relative to said shaft, a rod loosely mounted axially in said shaft, a segment shifting member attached to one end of said rod, a rod shifting means rotatably carried by said shaft and threaded onto said rod, electric operating means for rotating said rod shifting means independently of the rotation of said shaft to thereby shift said segments from a collapsed to an expanded position, coacting means carried by said rod and said shaft for holding said rod against rotary movement relative to said shaft while permitting longitudinal movement of said rod, an electric control means for said operating means, said operating means including a power member, electro-magnetic clutching means connected with said control means for coupling said power member with said rod shifting means, said control means including a circuit making and breaking means, and means carried partly by said shaft and partly by said rod shifting means for moving said circuit making and breaking means lengthwise of said shaft upon rotation of said shifting means relative to said shaft.

19. In a sheet rolling mill or other processing equipment, a sheet winding means comprising a rotatable overhung shaft and a collapsible drum carried by said shaft, said drum including a plurality of arcuate members loosely carried by said shaft, means at each end of said members holding said members on said shaft for movement relative to said shaft, correlated means carried by said shaft, said members and said holding means for effecting radial movement of said members simultaneous with longitudinal movement, means at one end of said shaft engaging the adjacent ends of said members for shifting said members longitudinally of said shaft, a cylinder attached to the opposite end of said shaft, a piston slidable in said cylinder, means connecting said piston to said shifting means, and pressure means connected to said cylinder for effecting movement of said piston in a selected direction.

20. In a sheet rolling mill or other processing equipment, a sheet winding means including a rotatable overhung sheet winding shaft, combined radially and longitudinally shiftable arcuate drum forming members carried by said shaft, correlated means carried partly by said shaft and partly by said members for radially shifting said members upon longitudinal movement thereof, means carried by each member partly overlapping an adjacent member whereby to form a smooth exterior surface when said members are in extended position, a segment shifting means slidable axially of said shaft and extending therethrough, and hydraulic means operatively connected with said shifting means for longitudinally shifting said members.

21. In a sheet rolling mill, a sheet winding means including a rotatable shaft for winding the sheet, combined radially and longitudinally shiftable segments carried by said shaft, means slidable through said shaft and coupled with an end of each segment for shifting said segments longitudinally of said shaft, correlated means carried partly by said segments and partly by said shaft for shifting said segments radially simultaneously with the longitudinal shifting thereof, each segment having a coil receiving channel therein, and electro-magnetic coils seated in said channels to thereby magnetize said segments and effect adherence of the leading end of the sheet

thereto to thereby wind the sheet about said segments upon rotation of said shaft.

22. In a sheet rolling mill, a sheet winding means comprising a rotatable winding shaft, means supporting said shaft for rotation, said supporting means engaging said shaft adjacent one end and at an intermediate point to thereby dispose the opposite end of said shaft in projecting relation from said supporting means, a collar fixed to said shaft on the projecting portion thereof adjacent said supporting means, a collapsible cylindrical electro-magnetic winding drum mounted on said projecting shaft portion, means releasably holding said drum on said shaft, contact members carried by the inner end of said drum, spring-pressed contact members carried by said collar engageable with said first contact members, and means connecting said second contact members to a source of electric current supply.

23. In a sheet rolling mill, a sheet winding means comprising a rotatable winding shaft, means supporting said shaft for rotation, said supporting means engaging said shaft adjacent one end and at an intermediate point to thereby dispose the opposite end of said shaft in projecting relation from said supporting means, a collar fixed to said shaft on the projecting portion thereof adjacent said supporting means, a collapsible cylindrical electro-magnetic winding drum mounted on said projecting shaft portion, means releasably holding said drum on said shaft, contact members carried by the inner end of said drum, spring-pressed contact members carried by said collar engageable with said first contact members, and means connecting said second contact members to a source of electric current supply.

24. An electro-magnetic winding drum for use on a sheet winding shaft comprising a collapsible cylindrical metallic body formed in the outer surface thereof with a plurality of longitudinal coil receiving channels, electro-magnetic coils in said channels, means closing said channels, terminals counter-sunk in an end of said body and connected to the ends of said coils, a retaining ring at one end of said body overlapping a portion of the latter, and spring pressed contacts carried by said ring engageable with said terminals.

25. In a sheet rolling mill or other processing equipment, a sheet winding means including a rotatable shaft, a plurality of elongated segments, means mounting said segments on said shaft for combined endwise and radial movement relative to said shaft, an arcuate inwardly projecting flange carried by one end of each segment, a segment shifting rod slidable through said shaft, means fixed relative to an end of said rod and engageable on opposite sides of said flanges whereby said segments will be shifted endwise with endwise movement of said rod, means fixed relative to said shaft and engageable with said segments adjacent the opposite ends thereof for slidably holding said segments in their radially and longitudinally adjusted positions, and means for shifting said rod lengthwise of said shaft.

26. In a sheet rolling mill or other processing equipment, a sheet winding means including a rotatable shaft, a plurality of elongated segments, means mounting said segments on said shaft for combined endwise and radial movement relative to said shaft, an arcuate inwardly projecting flange carried by one end of each seg-

ment, a segment shifting rod slidable through said shaft, means fixed relative to an end of said rod and engageable on opposite sides of said flanges whereby said segments will be shifted endwise with endwise movement of said rod, a pair of oppositely extending slide members carried by each segment one adjacent each end thereof, guide means for said slide members fixed to said shaft, and means for shifting said rod lengthwise of said shift.

27. In a sheet rolling mill or other processing equipment, a sheet winding means including a rotatable shaft, a plurality of elongated segments, means mounting said segments on said shaft for combined endwise and radial movement relative to said shaft, an arcuate inwardly projecting flange carried by one end of each segment, a segment shifting rod slidable through said shaft, means fixed relative to an end of said rod and engageable on opposite sides of said flanges whereby said segments will be shifted endwise with endwise movement of said rod, a pair of oppositely extending slide members carried by each segment one adjacent each end thereof, annular arcuately slotted collars fixed to said shaft and constituting guide means for said slide members, and means for shifting said rod lengthwise of said shaft.

28. In a sheet rolling mill or other processing equipment, a sheet winding means including a rotatable shaft, a plurality of elongated transversely arcuate segments about said shaft, means mounting said segments for combined endwise and radial movement relative to said shaft, an arcuate inwardly projecting flange carried by one end of each segment, obtusely disposed oppositely extending slide means fixed to the opposite ends of each segment, guide means for said slide means fixed to said shaft, a segment shifting rod slidable axially through said shaft, a reduced axial stub carried by said shaft, an annular plate fixed to said rod, an annular flange carried by said plate slidably engaging said stub, a second flange carried by said plate engageable about the adjacent ends of said segments and constituting a limiting means for limiting the expansion of said segments, a flanged ring fixed to said plate and engageable against the inner sides of said arcuate segment flanges whereby axial movement of said plate will effect endwise movement of said segments, and means for moving said rod endwise.

29. In a sheet rolling mill or other processing equipment, a sheet winding means including a rotatable shaft, a plurality of elongated transversely arcuate segments about said shaft, means mounting said segments for combined endwise and radial movement relative to said shaft, an arcuate inwardly projecting flange carried by one end of each segment, obtusely disposed oppositely extending slide means fixed to the opposite ends of each segment, guide means for said slide means fixed to said shaft, a segment shifting rod slidable axially through said shaft, a reduced axial stub carried by said shaft, an annular plate fixed to said rod, an annular flange carried by said plate slidably engaging said stub, a second flange carried by said plate engageable about the adjacent ends of said segments and constituting a limiting means for limiting the expansion of said segments, a flanged ring fixed to said plate and engageable against the inner sides of said arcuate segment flanges whereby axial movement of said plate will effect endwise movement of said segments, means for moving said rod endwise, and

means holding said rod against rotary movement relative to said shaft.

30. In a sheet rolling mill, a sheet winding means including a rotatable shaft for winding the sheet, radially and longitudinally shiftable segments carried by said shaft, means for simultaneously shifting said segments radially and longitudinally from a contracted wound sheet releasing position to an expanded sheet winding position, electro-magnetic means carried by and embedded in said segments for magnetizing the latter, terminals carried by an end of each segment, a ring fixed to said shaft overlapping the adjacent ends of said segments, and spring-pressed contacts carried by said ring engaging said terminals.

31. In a sheet rolling mill, a sheet winding means including a rotatable shaft for winding the sheet, radially and longitudinally shiftable segments carried by said shaft, correlated means carried by said shaft and said segments for radially shifting said segments upon longitudinal movement thereof, means extending through said shaft and engaging an end of each segment for shifting the latter longitudinally, a retaining ring fixed to said shaft and overlapping the opposite ends of said segments, means for magnetizing said segments, electric conducting means for energizing said magnetic means terminating in fixed terminals in said opposite ends of segments, spring-pressed contact means in said ring engageable with and maintaining contact against said fixed terminals in said opposite ends when said segments are shifted longitudinally and radially.

32. In a sheet rolling mill, a sheet winding means including a rotatable shaft for winding the sheet, drum forming segments about said shaft, correlated means carried by said shaft and said segments for radially shifting said segments upon longitudinal movement of the latter, electro-magnetic means carried by said segments for releasably holding a ferrous sheet thereon, means extending through said shaft connected to the ends of said segments at one end of the drum for shifting said segments longitudinally of said shaft independent of the rotation of said shaft, longitudinal extensions at the opposite ends of each segment, and means fixed relative to said shaft engaging said extensions for holding said segments about said shaft.

33. In a sheet rolling mill, a sheet winding means including a rotatable supporting shaft, a collapsible drum carried by said shaft, said drum including radially and longitudinally shiftable segments, correlated means carried by said shaft and said segments for shifting said segments radially upon longitudinal shifting thereof, a rod extending axially through said shaft, correlated means carried by one end of said rod and said segments for shifting said segments longitudinally with longitudinal movement of said rod, a rod operator rotatably carried by said shaft, correlated means carried by said rod and said operator for shifting said rod longitudinally of said shaft, said latter means being so constructed and arranged as to lock said rod in adjusted position, locking of said rod also locking said segments in extended or contracted position, and means for rotating said operator.

34. In a sheet rolling mill, a sheet winding means including a rotatable supporting shaft, a collapsible drum carried by said shaft, a drum collapsing and extending rod extending axially through said shaft, correlated means carried by one end of said rod and said drum for positively

moving said drum to extended or collapsed position upon endwise movement of said rod, means holding said rod against rotary movement relative to said shaft, threads carried by the opposite end of said rod, a rod operator threadably engaging said threads, means rotatably mounting said operator on said shaft, and means for rotating said operator independently of said shaft to thereby move said rod endwise in a selected direction.

35. In a sheet rolling mill, a sheet winding means including a rotatable supporting shaft formed with spaced inclined surfaces, a collapsible drum formed of a plurality of segments carried by said shaft, said segments having inclined surfaces contacting with said first surfaces, a drum collapsing and extending rod disposed axially of said shaft, means slidably holding said rod against rotary movement relative to said shaft, means fixed to said rod engaging the adjacent ends of said segments for positively shifting said segments endwise upon endwise movement of said rod in a selected direction, and means for moving said rod endwise to thereby extend or retract said drum.

36. In a sheet rolling mill or other processing equipment, a sheet winding means including a rotatable overhung shaft for winding the sheet, combined radially and longitudinally shiftable segments carried by said shaft forming a cylindrical drum, said shaft and segments having cooperating surfaces inclined to the longitudinal axis of said shaft, means for shifting said seg-

ments on and between said surfaces from a contracted wound sheet releasing position to an expanded sheet winding position, said shifting means including means for also shifting said segments from an expanded sheet winding position to a contracted wound sheet releasing position, said shifting means including a part slidably lengthwise of said shaft and operable from one end thereof.

- 10 37. In a sheet rolling mill, a sheet winding means including a rotatable supporting shaft, a collapsible drum carried by said shaft, said drum including radially and longitudinally shiftable segments, said shaft and said segments having cooperating surfaces so constructed and arranged that endwise movement of said segments will provide simultaneous radial movement of the latter, correlated means carried by said shaft and said segments for shifting said segments radially upon longitudinal shifting thereof, a rod extending axially through said shaft, correlated means carried by one end of said rod and said segments for shifting said segments longitudinally with longitudinal movement of said rod, a rod operator rotatably carried by said shaft and correlated means carried by said rod and said operator for shifting said rod longitudinally of said shaft, said operator being so constructed and arranged as to lock said rod in adjusted position, locking of said rod also locking said segments in extended or contracted position.

FRANK L. WETTENGEL.
